OPERATION PROCEDURE FOR GAS LIFTS

William W. Weinrich, Wallingford, Pa., assignor
to Houdry Process Corporation, Wilmington,
Del., a corporation of Delaware

Application June 14, 1950, Serial No. 168,026

2 Claims. (Cl. 302—66)

1 This invention relates in general to cyclic conversion systems in which solid contact material is passed by gravity flow along a down-flow path, wherein the material is contacted by gaseous reactants, and is then elevated by gas-lift action along an up-flow path. In particular, the invention relates to those cyclic conversion systems in which the aforementioned elevation of contact material is effected by engaging the material within a zone established about the lower open end of the lift path, with lift gas introduced into the engaging zone in a plurality of streams, one of which contains the major portion of the lift gas and functions primarily as the lift medium, and the remaining of which contain a minor portion of the total lift gas, insufficient in quantity to alone effect the desired lifting, but functioning primarily as a process control medium for controlling the flow rate of the contact material. The method of the invention may, for example, be applied to the system disclosed in my copending application, Serial No. 147,126 filed jointly with John W. Delaplaine on March 1, 1950, one embodiment of which discloses the elevation of contact material in the following manner: At the lower end of the down-flow path the contact material is introduced into an engaging zone surrounding the lower end of the lift path and gravitates therein as a compact moving bed around the lower portion of the lift path; lift gas is introduced into the engaging zone to engage the contact material and convey the same by entrainment upwardly through the lift path, the major portion of the lift gas being introduced into the engaging zone in a stream discharging adjacent to the lower periphery of the lift path, and a minor portion thereof being introduced in a stream which passes upwardly from the lower region of the engaging zone through at least a portion of the moving bed.

Specifically the invention is directed to procedures for interrupting and restarting the operation of the lift while shutting down or starting up such systems, and has for its primary object the provision of a sequence of operations by which the flow of lift gas and contact material may be stopped and subsequently restarted without adverse affect upon the operation of the system as a whole or upon the utility requirements for bringing the lift up to its normal conditions of operation. In the operation of such systems, periodic shut-downs for various known reasons are anticipated, and it is therefore essential to adopt those procedures in shutting down and starting up which will impose a mini-

2 mum of hardship on the system and minimize erratic behavior of the lift. Various procedures are usually available for stopping and starting lift operation, but most of them have the disadvantages of being too slow or of permitting the accumulation of substantial quantities of contact material in the lift pipe and introduction chamber after the flow of lift gas has ceased, as is the case when the total supply of lift gas is simply shut off, which may require upon restarting, a gas pressure considerably in excess of the maximum gas pressure normally necessary for catalyst lift purposes in order to overcome the pressure drop in the static bed of accumulated contact material. In the latter case, lift operation could not be resumed without either withdrawing a portion of the contact material from the introduction chamber, or employing an auxiliary pressure source, either of which represents additional expense and operating difficulty.

In accordance with the present invention, gas lifts which employ a primary lift gas stream for purposes of providing the major lifting force and a secondary gas stream functioning principally as a process control means, may be shut down in a minimum of time and suitably conditioned for restarting by the operations of first, shutting off the flow of process control gas into the engaging zone, so as to quickly reduce both the rate of solids flow into the lift pipe and the lift pressure drop to relatively small values and, second, shutting off the flow of primary lift gas into the engaging zone to interrupt solids flow entirely. When the primary stream of lift gas is shut off, the contact material ceases to circulate and the small quantity of contact material within the lift pipe which is unable to complete its travel upwardly through the entire lift path settles back at the bottom of the lift pipe and, together with material moving inwardly by gravity flow from the moving bed, fills the gap which existed between the lower end of the lift pipe and the bottom of the introduction chamber or, in some cases, the static layer of material in the bottom of the introduction chamber. By shutting down lift operation in the above manner, a subsequent start-up may readily be effected simply by reversing the procedure and introducing the primary stream of lift gas into the engaging zone to clear out the slight solids accumulation and to start circulation of the contact material. When the circulation becomes steady, the secondary stream or streams of lift gas may be introduced

to bring the circulation rate up to the desired value.

The foregoing procedure with respect to shutting down the lift accomplishes merely an interruption of solids and gas flow, but such interruption is effected with a minimum of time loss. For this reason, it is especially advantageous when, for any reason, it is urgent to quickly stop the lift operation.

In the normal operation of conversion systems of the type referred to herein, however, there may exist various reasons for shutting down the system and interrupting circulation of contact material, such as the need for inspection or repair of the introduction chamber or of any portion of the treating equipment located in the downflow path. In such cases, it is necessary to cut off the flow of contact material at some point in the downflow path above the point at which inspection or repair is to be effected. Suitable points for cutting off contact material flow, for example, may be found in the feed line or seal leg connecting the lowermost treating zone in the downflow path with the introduction chamber, in the seal leg connecting any adjacent treating zones in the downflow path, or in the feed line or seal leg through which the contact material initially passes at the start of its downward flow. Flow control valves of conventional type are usually available at these points. To permit withdrawal of contact material from the circulatory system it is conventional practice to provide storage facilities for the same at a point of elevation in the system from which the contact material may be passed by gravity flow back into the circulatory path. If the object in interrupting lift operation is to drain a portion of the system, the flow control valve nearest above said portion is shut off, either before or after the stream of secondary lift gas is shut off. At the same time, the valve which controls solids flow into storage is opened, so that the solids may pass from the upper end of the lift path into a storage vessel, and the lift operation is continued until the level of contact material in the downflow path below the point of interrupted solids flow has fallen sufficiently to clear that portion of the system to which access is desired. If process control gas has first been cut off, such solids evacuation will naturally proceed at a rate lower than the circulation rate at which the lift had previously been operating.

In addition to the foregoing procedures for effecting a sudden shut-down of the lift, and for effecting a shut-down coincident with drainage of contact material from a portion of the system, there is an additional procedure for shutting down the lift system. If the circulation of contact material is to be interrupted without removing any substantial quantity of contact material from the circulatory system and there is no necessity for haste, a shut-down of the lift may be effected by shutting off first the supply of process control gas to quickly reduce the solids flow rate in the lift pipe to a relatively low value; second, shutting off the valve in the solids inlet line; and third, gradually shutting off the supply of primary lift gas.

Each of the procedures described herein may effect a shut-down of the system with a minimum of residual or settled contact material in the lift pipe. In any case, however, provided sufficient time is available, the lift may be cleared of substantially all solids prior to complete shut-down merely by slowly closing the valve control-

ling the flow of primary lift gas after the secondary gas has been shut off.

For a fuller understanding of the invention, reference may be had to the accompanying drawing, forming a part of this application, which diagrammatically illustrates a typical hydrocarbon conversion unit and includes a gas lift to which the shut-down procedure of the present invention may be applied. Since the system illustrated is a typical hydrocarbon conversion system, such as a catalytic cracking unit, the contact material is a catalyst, and will hereinafter be referred to as such.

In the drawing, the conversion unit embodies a circulatory system for catalyst which may be in the form of pellets or granules having a particle size in the order of about 0.05 to 0.5 of an inch, or having, for example, an average particle size in the order of 14 mesh or larger. The circulatory system comprises separate down-flow and up-flow paths, generally indicated by the numerals 11 and 12, respectively. The catalyst continuously circulates through the system, while undergoing contact with gaseous reactants or separation from gaseous products of reaction in the down-flow path, and being elevated by entrainment in a gaseous lift medium in the up-flow path. A second down-flow path, generally indicated by the numeral 13, includes storage facilities for contact material which may temporarily be withdrawn from the circulatory system. The flow paths 11, 12 and 13 terminate in an upper lift hopper 14 and a lower lift hopper 15.

The catalyst is maintained as a compact moving bed 16 in the upper lift hopper 14, and is continuously supplied to the bed from the up-flow path or lift pipe 12. The catalyst is continuously withdrawn from bed 16 and passed as a downwardly moving column through a seal leg 17, controlled by valve 18, into the upper end of a reaction chamber 19. Within the reaction chamber 19, the catalyst is successively contacted under reaction conditions with vaporous hydrocarbons in order to carry out the desired hydrocarbon conversion, and is then purged of the gaseous products of reaction before discharging from the lower end of the reaction chamber into the seal leg 21. In passing through the reaction chamber the catalyst continuously gravitates as a compact non-turbulent bed.

The purged catalyst discharging from the lower end of reaction chamber 19 passes downwardly through seal leg 21, controlled by valve 22, and is introduced into the upper end of a kiln or regenerator 23. In a well-known manner, the contaminated catalyst is reactivated in the kiln by contact with a combustion-supporting gas, such as air, which burns off the carbonaceous deposit on the catalyst. The reactivated catalyst discharges from the lower end of regenerator 23 and passes as a downwardly moving column through seal leg 24, controlled by valve 25 into the lower lift hopper 15, the latter being the introduction chamber for the lift system.

Since a detailed description of the reactor 18 and the regenerator 23 are not considered essential for an understanding of this invention, the following brief description is believed sufficient. The hydrocarbon vapors may be introduced into the reaction zone 19, through inlet 26 in the upper region thereof, and the gaseous reaction products may be withdrawn therefrom through outlet 27, the flow of catalyst and gaseous material being concurrent. Purging gas,

5

such as steam, may be introduced through inlet 28 into the lower region of reaction chamber 19 for countercurrent flow with respect to the downwardly moving catalyst, and the purged hydrocarbon vapors may be withdrawn from the reaction zone through the outlet 27.

Seal gas, for the purpose of preventing the passage of hydrocarbon gases from the reaction zone 19 into the upper lift hopper 14, may be supplied to the upper region of chamber 19 through seal gas inlet 29.

In connection with the regenerator 23, the air or other combustion-supporting gas may be introduced through inlet 31, and the gaseous products of combustion, or flue gas, may be withdrawn through outlet 32. Sealing gas, to prevent intermixing of the reactor and regenerator gases, may be supplied to the upper region of chamber 23 through seal gas inlet 33.

Within the lower lift hopper or introduction chamber 15 the catalyst gravitates as a compact downwardly moving bed 34. The lower end of the lift pipe or up-flow path 12 projects centrally into the introduction chamber 15 and terminates in the lower region thereof, below the level of the catalyst bed 34. The lower end of the lift pipe is surrounded by a concentric sleeve 35 radially spaced from the lift pipe so as to provide an annular path 36 extending vertically from a point within the bed adjacent the lower end of the lift pipe to a point in the catalyst-free upper region of the introduction chamber, above the level of the moving bed. The sleeve 35 is suspended from a fixed collar frame 37 attached to the lift pipe 12 at a point above the introduction chamber by means of adjustable link member 38 extending downwardly through slip joints 39 in the upper head of the introduction chamber.

In the embodiment illustrated, lift gas is introduced into the introduction chamber 15 at two points, one within the catalyst-free space 41 in the upper region of the chamber, and the other within the catalyst bed 34 below the lower end of the lift pipe 12. The major portion of the total lift gas, which may be called primary gas, is introduced above the bed 34 through inlet line 42, controlled by valve 43. Substantially all of this gas passes downwardly through passage 36. The minor portion of the lift gas, which may be called secondary or diffuser gas, is introduced into the bed 34 through inlet line 44, controlled by valve 45. The primary gas, which provides the major lifting effect, and the secondary or diffuser gas, which is intended primarily for control purposes, may be the same gas or different gases. In any case, it is contemplated that the secondary or diffuser gas shall be in such minor amount, up to about 35% by volume of the total lift gas, as to be insufficient alone to effect the desired lifting. If both gases are to be the same, the secondary stream may comprise a portion of the stream supplied through line 42, which portion may be by-passed through line 46 under the control of valve 47. With the latter arrangement, the total supply of lift gas may readily be held constant while the proportion of primary and secondary gases may be varied. The system is not necessarily restricted to the use of any particular gases for lifting purposes, but there is an obvious limitation that there be no undesirable mixing of incompatible gases in the system.

The downflow path 13 is provided for hot catalyst storage during periods in which there has

6

been a withdrawal of all or a part of the catalyst in the circulatory system. To effect such withdrawal, the catalyst in bed 16 of the upper lift hopper 14 is continuously withdrawn through line 48, controlled by valve 49, and passed into storage hopper 51. If valve 18 in the seal leg 17 is shut off, and the lift operation continued, substantially all the catalyst in the downflow path 11 will be drained therefrom and passed to the storage hopper. Obviously, an interruption of catalyst flow at any intermediate point in the downflow path will cause only the catalyst below that point to be drained and passed to storage.

When lift operation is to be restarted, the stored catalyst in hopper 51 is returned to the circulatory system by being passed through conduit 52, controlled by valve 53, into the upper end of lower lift hopper 15.

In restarting after an emergency shut-down, the operations are reversed. The various control valves in the down-flow path 11 are opened and the valve controlling primary gas introduction is opened to permit the flow of sleeve air through the annular passage 36. The valve 49 at the upper end of down-flow path 13 is closed, and valve 53 at its lower end is opened to permit stored catalyst to flow into the lower lift hopper. When the catalyst flow effected by the primary gas has become uniform, the valve controlling the flow of diffuser gas through inlet line 44 is opened and the flow of diffuser gas is regulated to bring the catalyst circulation rate up to the desired value.

To illustrate the results obtainable by the procedure of this invention, reference may be had to the following example of the operation of a 12-inch lift pipe, using air as the lifting medium, before and after the supply of diffuser air was cut out.

Example

	Before	After
45 Total Air Rate (S. C. F. M.)	2,710	2,250
Percent of Total Air to Diffuser	17	0
Catalyst Rate (Tons/hr.)	90.95	13.3
Introduction Chamber Pressure (p. s. i. g.)	4.5-5.0	1.2-1.4

When the lift had attained equilibrium at the "after" operating conditions, as indicated by a substantially constant pressure drop, the primary or sleeve gas was shut off, thus interrupting the upward flow of catalyst and reducing the pressure drop to zero. To resume operation, the sleeve air was set to substantially its previous value, and the unit was again permitted to come to equilibrium. Then diffuser air was slowly added until the desired catalyst rate was reached. For the conditions existing in the "after" column of the above table, the lift pressure drop when restarting the lift in this manner varied between 1.0 and 1.9 p. s. i. g. until the air and catalyst flows were established. Then the lift pressure drop returned to its former value between 1.2 and 1.4 p. s. i. g. It was thus clearly demonstrated that lift operation could be easily restored to normal without supplying lift gas in excess of the total lift gas requirement for normal operation.

Applying the preferred procedure to a typical lift system, for example, one in which the lift height is 175 feet, the lift diameter is 12 inches, and the sleeve height, as defined in the aforementioned copending application, is such as to produce a lift pressure drop of about 0.1 to 3.0

p. s. i. g. when diffuser air is shut off, the catalyst circulation would range from less than 5 tons/hour to nearly 100 tons/hour. With the diffuser air turned on in normal operation, the lift pressure drop would increase to a range of about 1.0 to about 12 p. s. i. g., and the range of catalyst circulation rates would increase to 10-270 tons/hour.

While the procedure for shutting-down and starting-up the lift has been described particularly in connection with the lift introduction chamber illustrated in the drawing, it is to be understood that it is not so limited. The procedure may be applied with equal advantage to any lift inlet system embodying an introduction chamber into which lift gas is introduced in separate streams, one of which introduces lift gas in major proportion to effect the desired lifting, and the other of which introduces a minor amount of additional lift gas primarily for control purposes. Regardless of how engagement between the particles of catalyst and the lift gas is effected, a rapid shut-down of lift operation is obtained in accordance with the present invention by first reducing the catalyst circulation to the minimum value obtainable by elimination of secondary or process control gas, and then cutting off the flow of primary gas. The latter operation being timed to permit the lift to evacuate the desired amount of catalyst from the lower lift hopper, or to drain the necessary amount of catalyst from down-flow path 11.

The foregoing procedure provides a simple, efficient method for shutting down a gas lift of the character herein described by which there may be accomplished first, a substantially immediate evacuation of the major portion of the solids passing through the lift pipe accompanied by a considerable reduction in the solids concentration and solids flow rate therein and, second, an interruption of the solids flow at a time when there is a minimum of solids within the lift pipe which may settle at the bottom thereof when the flow of gas has ceased.

Although in most instances, it may be preferred to gradually shut off the flow of primary gas in order that there may be almost complete evacuation of the lift pipe by the time gas flow ceases, in the event that insufficient time is available for a gradual shut off of the primary stream, its sudden interruption will still leave within the lift pipe a quantity of solids so small that restarting of the lift with gas at the pressures and in the quantities normally available is assured.

5 10 15 20 25 30 35 40 45 50 55

What is claimed is:

1. In the operation of a gas lift forming the up-flow path of a pressure balanced system through which granular material is continuously circulated, which system includes a down-flow path wherein said material gravitates as a compact non-turbulent mass enveloping, at the lower end thereof, the lower end of the lift path, the elevation of said material being effected by introducing the major portion of the lift gas into said mass in a confined stream discharging immediately adjacent the lift path inlet and the minor portion thereof into said mass at a point remote from said lift path inlet but in such proximity thereto as to provide the principal flow rate control for said material, the method of shutting down said lift which comprises the sequential steps of: cutting off the flow of said minor portion of the lift gas, thereby reducing said flow rate to a relatively low value, cutting off the gravitational flow of said granular material at a point along said down-flow path, withdrawing from the upper end of said up-flow path at least a portion of the total granular material contained within said lift path and with in the portion of said down-flow path below said point, and cutting off the flow of said major portion of the lift gas so as to interrupt the circulation of said granular material, whereby upon said interruption, a minimum of said granular material remains within said lift path to settle and form an accumulation at the lower end of said lift path.
2. A method as defined in claim 1 in which said withdrawal of granular material from the upper end of said lift path is continued until substantially all of said total granular material has been withdrawn from the circulatory system.

WILLIAM W. WEINRICH.
